UNITED STATES PATENT OFFICE.

HENRY W. PLEISTER, OF WESTFIELD, NEW JERSEY, ASSIGNOR TO HENRY B. NEWHALL.

BOLT-ANCHOR.

1,222,988.

Specification of Letters Patent. Patented Apr. 17, 1917.

Original application filed October 16, 1915, Serial No. 56,239. Divided and this application filed March 17, 1916. Serial No. 84,896.

To all whom it may concern:

Be it known that I, HENRY W. PLEISTER, a citizen of the United States, and a resident of Westfield, in the county of Union 5 and State of New Jersey, have invented certain new and useful Improvements in Bolt Anchors, of which the following is a specification taken in connection with the accompanying drawings, which form a part of 10 the same.

This application is a division of my pending application Ser. No. 56,239 filed October 16, 1915, for "bolt anchors and method of making same".

15 My present invention relates to a new and improved bolt anchor in which the screw-threads of the screw cut their own co-operating female screwthreads in the bolt anchor. In this form my bolt anchor is made out of 20 a comparatively soft metal such as a lead alloy or similar material, which is softer than the metal of the wood screw, or lag bolt, should the latter be used. In this art relatively soft bolt anchors, in which the wood 25 screw cuts its own co-operating female screw-threads, are known as "anchors," "lead anchors" and "screw anchors".

More specifically my invention relates to such an anchor, lead anchor or screw anchor, 30 which can be manufactured at the minimum expense due to the saving of material.

My invention further relates to a relatively soft rod or bar having a plurality of 35 units, the units having open sides, whereby one or more units may be broken off to form an anchor, lead anchor or screw anchor of the required holding capacity.

I have shown in the accompanying drawings 40 several illustrative embodiments of my invention, but of course it is to be understood that my invention is not to be confined simply to the forms illustrated. In these drawings the same reference numerals refer 45 to similar parts.

Figure 1 is a side elevation, partly in vertical section of one of my improved anchors;

Fig. 2 is a view partly in side elevation 50 and partly in vertical section of one of my anchor rods or bars which may be used as one anchor, or which may be broken into one or more units, if an anchor of less holding capacity is required;

Fig. 3 is a vertical section of one ductile 55

unit broken from the rod or bar illustrated in Fig. 2;

Fig. 4 is a side elevation of the preferred form of my anchor, formed of two units, and shown mounted in a hole or support and prior to being expanded, the support being shown in section;

Fig. 5 is a vertical section through my improved anchor after it has been expanded by the screw shown, or any other suitable means, the support and the article supported being shown in section;

Fig. 6 is an end elevation substantially on the line 6—6 of Fig. 4, looking in the direction of the arrows, showing the units forming a substantially cylindrical anchor and prior to their expansion;

Fig. 7 is an end elevation substantially on the line 7—7 of Fig. 5 looking in the direction of the arrows and showing the anchor 75 expanded. In this figure, as well as in Fig. 6, the support is omitted for the purpose of clearer illustration; and

Fig. 8 is an end elevation and vertical section substantially on the line 8—8 of Fig. 2. 80

In the illustrative embodiments of my invention shown in the drawings, 1 is an anchor formed preferably of two or more units 2 and 3, the unit 2 having an open side 4 and the unit 3 having an open side 5, the open sides being at an angle to each other and preferably formed staggered. Between each unit and its adjacent unit there is a connecting member formed of two arms 6, 6.

The open side 4 is provided with an inclined surface 7, and the open side 5 is provided with an inclined surface 8, the two inclined surfaces being at an angle to each other. These two inclined surfaces 7 and 8 form an inclined bore 9 which is interrupted or broken opposite the open sides 4 and 5 of the units.

I preferably, though not necessarily, form the units 2 and 3, so that in their unexpanded position they will substantially form a cylinder which, of course, would not be continuous throughout the length of the bolt anchor due to the units 2 and 3 having open sides.

In locating my anchor in a wall or other support 10 the hole 11 is drilled or otherwise formed substantially at right angles to the face 12 of the support, the hole being about the same depth as the length of the anchor. The length of the latter is determined by the 110

number of units, one or more, to obtain the desired holding capacity for that particular anchor. Where there is but little strain or stress to be carried one unit 2 may be used, 5 Fig. 3, or two units may be used as shown in Figs. 1, 4 and 5, or any greater number, as for example, that shown in Fig. 2.

After the anchor is inserted in the hole 11 the work to be supported 13 is brought up 10 flush with the surface 12 of the support 10 and the expanding member, as for example the wood screw 14, is passed through the work 13 and into engagement with the respective inclined surfaces 7 and 8 of the units 15 2 and 3. The wood screw will as it is screwed home, cut its own coöperating female screw-threads in the comparatively soft or ductile material of the inclined surfaces 7 and 8, and will cause a tremendous expansion, which in 20 the unit 1 for example, will begin some little distance back from the outer end 17 and reach its maximum, in that unit, at the point 18. On the other unit 3 the expansion will 25 progress from the point 19 and reach its maximum at the point 20. This action will insure a powerful gripping action between the anchor and the support, whether that support be brick, masonry, concrete, tile, stone or any other material.

30 I preferably, though not necessarily, provide the bolt anchor 1 with one or more lugs 21, which may be bent sufficiently to form a support for the wood screw 14, or other expanding member. These lugs may also hold 35 the wood screw to the anchor for purposes of shipping or storing.

In the expanding action which I have just described, the connecting member formed of 40 arms 6, 6 will of course bend slightly to permit of the expansion. I also preferably provide the exterior of my units with transverse ribs or corrugations 23, 23 to insure that they have stronger frictional hold 45 against the wall of the hole 11 in the support 10.

It will be clear that with my bolt anchor I obtain a tremendous expansion or holding 50 capacity using only a minimum amount of ductile or relatively soft metal, the saving of which permits me to manufacture my anchor at minimum expense.

The method of manufacturing my anchor is described in full in my copending applications Ser. No. 56,239 and Ser. No. 84,895, 55 filed concurrently with this divisional application. In this application Ser. No. 84,895 the method is claimed.

By my invention I may cast a ductile rod or bar 24, Fig. 2, of a plurality of units 25 60 and 26 which may be of any suitable length. For convenience in handling and shipping these ductile bars or rods 24 may be shipped direct to the jobber or retailer or user who may use the entire bar as one anchor or may 65 break off one or more of the ductile units to

obtain a smaller anchor and one of the particular holding capacity that he may need for the particular work to be supported. He may for example, break off one unit, Fig. 3, or he may break off two or more units, simply by severing the connecting member 6, 6 70 between any two units.

It will be seen when my anchor comprises two or more units, that their expansion is in opposite directions about a point intermediate the length of the anchor. It will also 75 be seen that my anchor has a plurality of points of maximum expansion arranged in different planes.

Having thus described this invention in connection with the illustrative embodiments thereof to the details of which I do not desire to be limited what is claimed as new and what it is desired to secure by Letters Patent is set forth in the appended claims.

1. An article of manufacture comprising an expansible ductile anchor having a plurality of open sides.

2. An article of manufacture comprising an expansible ductile anchor having a plurality of open sides arranged staggered with 90 relation to each other.

3. An article of manufacture comprising an expansible ductile anchor having a plurality of open sides and a central axial bore.

4. An article of manufacture comprising an expansible ductile anchor having a plurality of open sides, said sides having inclined surfaces at an angle to each other.

5. An article of manufacture comprising an expansible ductile anchor having a plurality of open sides arranged on different portions of the anchor.

6. An article of manufacture comprising an expansible ductile anchor formed of a plurality of units, each unit having an open side and a connecting bendable member between the units.

7. An article of manufacture comprising an expansible ductile anchor formed of a plurality of units, each unit having an open side and a connecting bendable and breakable member between the units.

8. An article of manufacture comprising a substantially cylindrical ductile anchor formed of a plurality of units, each unit having an open side, and a connecting bendable member between the units, said anchor being provided with an internal bore having a plurality of tapers.

9. An article of manufacture comprising an expansible ductile anchor having a plurality of open sides and an internal bore having a plurality of tapers.

10. An article of manufacture comprising an expansible ductile anchor rod formed of a plurality of units, each unit having an open side and bendable and breakable connecting members connecting the units to permit the rod to be used as one anchor, or 125 130

to permit an anchor of any required length and of one or more units being broken off from the rod to form a smaller anchor, said rod being provided with an internal bore 5 having a plurality of tapers.

11. An article of manufacture comprising an expansible ductile anchor having a plurality of open sides and one or more bendable lugs adapted to be bent to partly close 10 one of the open sides.

12. An article of manufacture comprising

a substantially cylindrical ductile anchor formed of a plurality of units, each unit having an open side, and a connecting bendable member between the units and one or 15 more bendable lugs adapted to be bent to partly close one of the open sides.
